REINKING MACHINE FOR TYPEWRITER RIBBONS

Leon L. Ogg, Creston, Iowa

Application November 4, 1942, Serial No. 464,487

5 Claims. (Cl. 91—54)

This invention relates to a machine for re-inking or re-conditioning typewriter ribbons or other printing ribbons to enable continuous use of the same base or fabric thereof.

It is particularly aimed to provide a novel machine through which the ribbon is passed and during which passage ink is applied to it and spread evenly in the desired quantity. And in which the ribbon is subjected to variable pressure to produce a squeegee effect thereon.

I further aim to provide a novel means for quickly enabling journaling of the spool from which the ribbon is unwound and the spool on which it is rewound.

In addition, it is aimed to provide a novel ink reservoir and means whereby it may be supported and refilling thereof is facilitated.

The more specific objects and advantages will become apparent from a consideration of the description following taken in connection with accompanying drawings illustrating an operative embodiment.

In said drawings:

Figure 1 is a plan view of the improved machine;

Figure 2 is a partial side elevation thereof;

Figure 3 is a central vertical longitudinal sectional view;

Figure 4 is a vertical transverse sectional view taken on the line 4—4 of Figure 3;

Figure 5 is a vertical transverse sectional view taken on the line 5—5 of Figure 3;

Figure 6 is a vertical transverse sectional view taken on the line 6—6 of Figure 3;

Figure 7 is a detail section taken on the line 7—7 of Figure 3;

Figure 8 is a detail section taken on the line 8—8 of Figure 1 and

Figure 9 is a detail sectional view showing a modified form for journaling the shafts of certain rolls.

Figure 10 is a vertical longitudinal section showing more clearly the disc and cam assembly.

Referring specifically to the drawings wherein like reference characters designate like or similar parts, the machine has a suitable skeleton frame work generally designated 10. The typewriter or other printing ribbon is shown at 11 and is treated by the machine after it fades or becomes worn in use in a typewriting machine and requires re-inking or further ink to enable reuse thereof, thus enabling the base or fabric of the ribbon to be used practically continuously. This ribbon as applied to the machine, is mounted on a spool 12 of conventional design, which in most cases will be the spool on which it is wound before removal

from the typewriting machine. Said spool 12 is gripped on opposite sides, at the usual central opening by the pointed ends of arbors 13 and 14 mounted in any suitable way as by vertical bearing blocks 15 riveted or otherwise secured at 16 to a cross member 17 at the top and right hand end of the frame 10. Each arbor 13 and 14 has a manipulating knob 18 at the free end thereof. Arbor 13 is secured in place normally against movement by a setscrew 19 and arbor 14 is secured in place normally against movement by a setscrew 20. A coil spring 21 surrounds the arbor 14 and is expansive, bearing at one end against the adjacent block 15 and at the other end against a disk 22 on the arbor, so that when the setscrew 20 is loose, the spring will urge the arbor 14 and disk 22 into effective contact with the spool 12 to journal the latter, the screw 20 being thereafter tightened to hold the arbor 14 against their movement. Said ribbon 11 is threaded beneath a roll 23 and between the latter and an ink applicator 24. Said applicator consists primarily of an endless strip or band of felt or other absorbent material traversing upper and lower rollers 25 and 26. Roll 23 is keyed to a shaft 27 journaled in any suitable manner on the frame 10, preferably with its ends mounted in suitable bearings or bearing openings thereof. Roll 25 is keyed to a shaft 28 while roller 26 is keyed to a short shaft 29, the latter being journaled in plate 30 loosely suspended on the shaft 28. A positioning hook 31 has one end of shaft 29 journaled in it and its hook end 32 is in detachable suspending engagement with the shaft 27.

The applicator 24 is obliquely disposed with its lower end portion in a trough or well 33 suitably mounted on the frame 10.

Ink is adapted to be supplied or flow by gravity into the trough 33 from a suitable reservoir 34 through an outlet fitting 35 and hose or conduit 36 whose discharge end is located in the trough. Fitting 35 is equipped with a suitable sight gage 37 and with a cutoff of regulating valve at 38.

Reservoir 34 has a filling opening which is normally lowermost as shown in the drawings and covered by a screw threaded cap or closure 39. Cap 39 has a tapered dependent 40 which is detachably engaged in a recess 41 provided in one of the side strips 42 of the frame 10. Reservoir 34 has a vent pipe 43 in communication with the atmosphere and capable of being closed by a valve 44 therein.

Reservoir 34 and all parts connected thereto are removable from the frame and capable of support on the normally upper surface of the reser-

voir 34, since all parts attached thereto are normally below the level of that surface. When thus supported or inverted, closure 39 may be removed to enable filling of the reservoir, following which the closure is applied to the reservoir and the parts restored to normal position with the dependent or lug 40 removably disposed in recess or socket 41.

Applicator 24 also in combination with the roll 23 has a squeegee effect on the ribbon to cause the ink to evenly penetrate the same and even distribution without excess ink being absorbed or carried thereby. To this end, roller 25 is vertically adjustable. The ends of shaft 28 are journaled in bearings 45 which are vertically slideable in slots or ways 46 provided in brackets 47 as parts of the side strips 42 of the frame. Said bearings 45 are nonrotatable as they have flat portions conforming to the vertical walls of the ways 46. Shaft 28 has loosed thereon, disk 48 and in contact therewith are cams 49 keyed to a shaft or rod 50 which is journaled in the frame 10 and at one end has a manipulating knob 51. Through turning of the knob 51, the cams 49 since they contact the peripheries of the disk 48, will cause raising or lowering of the shaft 28 and roller 25 thereon, with consequent regulation of the pressure of applicator 24 with respect to the roll 23 and the ribbon 11.

After passage over the applicator 24, ribbon 11 passes under a roll 52, thence upwardly and over a roll 53, thence downwardly under a roll 54, thence over a roll 55 and then to a rewinding roll 56. The shafts 51, 58 and 59, on which the rolls 52, 53 and 55 are respectively keyed, may be journaled in any suitable manner for instance in bearings 60, as detailed in Figure 8, which bearings are slidably adjustable and fastened to the frame in any suitable manner as by means of screws 61 passed through elongated slots 62 in the bearings.

The shaft 63 on which roll 54 is keyed may be journaled in the same way as the shaft 27. As an alternative way of journaling both the shafts 27 and 63, I may use cap bearings 64, as shown in Figure 9. These cap bearings or sockets receive the adjacent ends of the shafts 63 or 27 and the bearings have lugs or extensions 65 engaged in openings in the side strips 42 and fastened against turning therein by the binding action of setscrews 66 threaded in the side strips.

The rewind roller or reel 56 may be a conventional typewriter spool like that at 12 and another spool which is used in the winding mechanism for the ribbon in the typewriter. Reel 56 is gripped from opposite sides by shaft sections 67 and 68 journaled in the side strips 42 and bearings 69 of the frame 10, or in any other suitable manner. Shaft 68 has a relatively large disk 70 keyed to it which is adapted for frictional engagement against one side of the reel 56 as best seen in Figure 4. Shaft section 68 also has a reduced extension 71 which extends into the central opening of the reel 56. Shaft section 67 is pointed at 72 to also extend into the same opening and the frictional engagement between the plate 70 and shaft 67 with the reel is augmented by the expansive action of a coil spring 73 abutting one of the side strips 42 and a stop 74, fastened on the shaft. A knob for retracting or manipulating the shaft 67 is fixed thereon at 75.

The various rolls may be driven or rotated in any suitable manner. As shown, a pulley 76 is keyed to shaft 27 and adapted to be manually turned through operation of a crank 77. Trained over the pulley 76 is an endless belt 78 also trav-

ersing a pulley 79 keyed to the shaft 68. A balance wheel 80 may be keyed to the latter shaft. An endless belt 81 also traverses pulleys 82 and 83, respectively fixed on the shafts 27 and 63.

As a result of the construction described, it will be realized that the ribbon wound on the reel 12 is positioned in the machine through the positioning of the reel 12 as shown in Figures 1, 3 and 6, in particular that such ribbon is threaded in the manner shown and traced through the various rolls and in contact with the ink applicator 24 having a squeegee effect in combination with roll 23, to evenly and to the proper amount, re-ink such ribbon. The rewound ribbon is removed with the reel 56 and the same again used in the typewriting or other machine.

Various changes may be resorted to provided they fall within the spirit and scope of the invention.

I claim as my invention:

1. A machine of the class described having means to mount a reel from which an inking ribbon is unwound, means to mount a reel for rewinding of said ribbon, and means to apply ink to the ribbon in its passage from one reel to the other comprising a roll, a shaft therefor, an endless absorbent applicator engageable with the ribbon in opposition to the roll providing a squeegee action on the ribbon and applicator, a roll over which the applicator passes, a shaft for the latter roll, a second roll over which the applicator passes, means pivoted on the second mentioned shaft journaling the said second roll from the second mentioned shaft, means mounting the second mentioned roll, and an inkwell into which one end of the applicator extends.

2. A machine of the class described having means to mount a reel from which an inking ribbon is unwound, means to mount a reel for rewinding of said ribbon, and means to apply ink to the ribbon in its passage from one reel to the other comprising a roll, a shaft therefor, an endless absorbent applicator engageable with the ribbon in opposition to the roll providing a squeegee action on the ribbon and applicator, a roll over which the applicator passes, a shaft for the latter roll, a second roll over which the applicator passes, means journaling the said second roll from the second mentioned shaft, means pivoted on the second mentioned shaft mounting the second mentioned roll, and an inkwell into which one end of the applicator extends, said means mounting the second mentioned roller comprising a shaft, a plate journaling the latter shaft and mounted on the second mentioned shaft, and means engaging the first mentioned shaft and shaft of the second roller suspending the plate at one end from said first mentioned shaft.

3. A machine of the class described having means to mount a reel from which an inking ribbon is unwound, a second reel for rewinding of said ribbon, and means to apply ink to the ribbon in its passage from one reel to the other, comprising a roll, a shaft therefor, an endless absorbent applicator engageable with the ribbon in opposition to the roll providing a squeegee action on the ribbon and applicator, a roll over which the applicator passes, a shaft for the latter roll, a second roll over which the applicator passes, means pivoted on the second mentioned shaft journaling the said second roll from the second mentioned shaft, means mounting the second mentioned roll, and means to apply ink to the applicator, slideable bearing means mounting the second mentioned shaft, an eccentric means co-

acting with the second mentioned shaft and slideable bearing means so as to adjust the pressure of the applicator with respect to the first mentioned roll.

4. A machine of the class described having means to mount a reel from which an inking ribbon is unwound, means to mount a reel for rewinding of said ribbon, a second reel on said means, and means to apply ink to the ribbon in its passage from one reel to the other comprising a roll traversed by the ribbon, and an ink well, an ink applicator extending into the well and engaging the ribbon outside of the well in opposition to the roll providing a squeegee action on the ribbon and applicator.

15

5. A machine of the class described having means to mount a reel from which an inking ribbon is unwound, means to mount a reel for rewinding of said ribbon, a second reel on said means, and means to apply ink to the ribbon in its passage from one reel to the other comprising a roll traversed by the ribbon, and an ink well, an ink applicator extending into the well and engaging the ribbon outside of the well in opposition to the roll providing a squeegee action on the ribbon and applicator, and means to vary the pressure of the applicator with respect to the roll and ribbon.

LEON L. OGG.
